CLAIM

I claim the ornamental design for a drawer divider, as shown and described.

DESCRIPTION

FIG. 1 is a perspective view of a first embodiment of a drawer divider in a closed configuration showing the new design;

FIG. 2 is a perspective view of the first embodiment of the drawer divider in an extended configuration;

FIG. 3 is a right side view thereof, the left side view being identical thereto;

FIG. 4 is a front view thereof;

FIG. 5 is a rear view thereof; and

FIG. 6 is a top view thereof, the bottom view being identical thereto.

FIG. 7 is a perspective view of a second embodiment of a drawer divider in a closed configuration showing the new design;

FIG. 8 is a perspective view of the second embodiment of the drawer divider in an extended configuration;

FIG. 9 is a right side view thereof, the left side view being identical thereto;

FIG. 10 is a front view thereof;

FIG. 11 is a rear view thereof; and,

FIG. 12 is a top view thereof, the bottom view being identical thereto.

The drawer divider is shown with symbolic breaks in its height. The appearance of any portion of the drawer divider between the break lines forms no part of the claimed design.
